US00D894835S

(12) **United States Design Patent** (10) **Patent No.:** **US D894,835 S**
Luo et al. (45) **Date of Patent:** **** Sep. 1, 2020**

(54) **MOTOR**

(71) Applicant: **Chongqing Zhenyoujin Technology Co., Ltd.**, Chongqing (CN)

(72) Inventors: **Kangbing Luo**, Chongqing (CN); **Jiankun Cui**, Chongqing (CN); **Yong Zeng**, Chongqing (CN); **Bo Peng**, Chongqing (CN)

(73) Assignee: **Chongqing Zhenyoujin Technology Co., Ltd.**, Chongqing (CN)

(**) Term: **15 Years**

(21) Appl. No.: **29/681,584**

(22) Filed: **Feb. 27, 2019**

(30) **Foreign Application Priority Data**

Aug. 27, 2018 (CN) 2018 3 0476344

(51) **LOC (12) Cl.** **13-02**

(52) **U.S. Cl.**

USPC **D13/122**; D13/118

(57) **CLAIM**

The ornamental design for a motor, as shown and described.

DESCRIPTION

FIG. 1 is a perspective view of a first embodiment of a motor showing our new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1;

FIG. 8 is a perspective view of a second embodiment of a motor showing our new design;

FIG. 9 is a front view of FIG. 8;

FIG. 10 is a rear view of FIG. 8;

FIG. 11 is a left side view of FIG. 8;

FIG. 12 is a right side view of FIG. 8;

FIG. 13 is a top view of FIG. 8; and,

FIG. 14 is a bottom view of FIG. 8.

The broken lines in the figure drawings of the claimed motor is included for the purpose of illustrating of the article and forms no part of the claimed design.

1 Claim, 10 Drawing Sheets
